LUMINAIRE FOR ELONGATED TUBULAR LAMPS

2 SHEETS—SHEET 2

UNITED STATES PATENT OFFICE

2,619,583

LUMINAIRE FOR ELONGATED TUBULAR LAMPS

George R. Baumgartner, South Euclid, Ohio, assignor to General Electric Company, a corporation of New York

Application October 21, 1947, Serial No. 781,112

3 Claims. (Cl. 240—51.11)

1

My invention relates to luminaires of the ceiling suspended type utilizing elongated fluorescent lamps.

An object of my invention is to provide an inexpensive luminaire of this type which is of simple structure easy to assemble and dismantle. Another object of my invention is to provide a stiff, shallow combined wiring channel and reflector member for supporting the lamps, lamp holders, lamp ballasts and other parts of such luminaires. Other objects and advantages of the invention will appear from the following detailed description of species thereof and from the accompanying drawings in which Fig. 1 is a perspective view of a luminaire embodying my invention and as seen from below; Fig. 2 is a side elevational, fragmentary view showing one end of the luminaire shown in Fig. 1; Fig. 3 is a transverse sectional view on an enlarged scale along the line 3—3 of Fig. 2; Fig. 4 is a fragmentary plan view of a part of the luminaire shown in Figs. 1 to 3; Fig. 5 is a transverse sectional view on a reduced scale of a support member providing a wiring channel and reflectors for a luminaire; Fig. 6 is a similar view of another support member of different structure; Fig. 7 is a perspective view of another luminaire of my invention as seen from below; Fig. 8 is a transverse sectional view on an enlarged scale along the line 8—8 of Fig. 7 and Fig. 9 is a sectional view along the line 9—9 of Fig. 8.

The luminaire illustrated in Figs. 1 to 4 of the drawing includes four elongated tubular fluorescent lamps 1, 2, 3 and 4 of the double-ended type each having a single contact pin or prong (not shown) at each end for engaging the lamp holders 5 and 6. Such lamps are commercially available in lengths up to approximately eight feet and suitable lamp holders therefor are also commercially available. Lamps of such length require an elongated rigid support. In the luminaire illustrated in Figs. 1 to 4 the support is in the form of a shallow, elongated, stiff, tubular metal member 7 of flattened cross-section the interior of which provides a wiring channel 8 (Fig. 3) and the side and bottom surfaces thereof reflectors for the lamps. As shown in Fig. 3 the bottom surface provides two trough shaped reflectors 9 and 10 which are elliptical in transverse section and the side surfaces 11 and 12 are curved to provide a portion of an elliptically shaped trough.

The lamp holders 6 at one end of the luminaire are secured to a transverse strap 13 constituting a lamp holder support attached to the top wall

2

14 of the support member 7 by threaded bolts 15 and 16 provided with spacers 17 and 18. The strap 13 has two vertical end portions 19 and 20 to each of which two holders 6 are attached in a horizontal position by a pair of threaded bolts 21 provided with nuts 22 and passing through the base end 23 of the holders 6 and through the end portions 19 and 20 of the strap 13. The holders 5 at the opposite end of the luminaire are attached to member 7 in the same manner. The lamps are thus supported in proper position with respect to the reflectors. The member 7 has suitable cut-out portions at its ends to accommodate the holders 5 and 6 as shown in Fig. 1.

15 The luminaire is supported by a pair of metal conduits or pipes 24 attached to each end thereof and adapted to engage an electrical ceiling outlet 25. Each of the pipes 24 has a threaded end 26 (Fig. 2) passing through an opening in the outer 20 end of a ballast cover 27 of metal, one at each end of the luminaire, attached to the top wall 14 of the support member 7 by bolts 28. Each of the pipes 24 is attached to a cover 27 by a lock nut 29 and a shoulder 30. The top wall 14 of the member 7 is cut out under each of the covers 27 (Fig. 3) to accommodate the usual elongated lamp ballasts, one in each cover 27, each having a metal casing 31. Each ballast is connected to two of the lamps and is supported partially in 25 the cover 27 and partially in the wiring channel 30 8 (Fig. 3) by bolts 32 at each end thereof engaging threaded metal buttons 33 welded to the top wall of the cover 27 and also engaging the brackets 34 welded to the usual ears 35 at the ends of 35 the ballast casing 31. The said ears 35 are cut out to accommodate the buttons 33 and the cut out portion thereof is bridged by the brackets 34.

The casings 31 are set back a sufficient distance from the outer end of the covers 27 to clear the 40 lamp holders 5 and 6 when they are inserted into and removed from the member 7. Access to the mounting space for the casings 31 is provided through an opening formed by cutting a portion of the bottom of the member 7 underneath the casings 31 so as to form doors 36 (Fig. 4). The 45 said doors 36 are held in place by a straight metal strap 37 (Fig. 3) welded or soldered to one end thereof and held by bolts 38 and 39 on the strap 13 supporting the lamp holders 5 and 6. 50 The other end of the doors 36 (Fig. 4) are held in place by an extension 40 which extends beyond the said end and rests on the adjacent parts of the reflectors 9 and 10. Access to the bolts 38 and 39 is provided through openings 42 and 55 43 (Fig. 3) in reflectors 9 and 10.

The open ends of the wiring channel 8 and covers 7 are closed by easily removable end plates 44 held in place by spring fingers (not shown) which frictionally engage the inner surfaces of the channel and the covers.

The two outer lamps 1 and 4 are shielded from view by the longitudinally extending shields 46 and 47 of translucent material, such as glass, organic plastic or perforated metal strips, which are supported by the arms 48 bolted to the member 7 10 and provided with spring clips 49 of phosphor bronze. I prefer to so dimension and position the reflectors 9, 10, 11 and 12 and the shields 46 and 47 with respect to the lamps 1, 2, 3 and 4 that the latter are shielded from direct view 15 from the side of the luminaire at viewing angles of about 35° to the horizontal. Also, I prefer to so mount the lamps 1 to 4 with respect to the elliptical reflectors 9 to 12 that the image of the lamps are also shielded from direct view from the 20 sides of the fixture at predetermined angles as described and claimed in the Allen Patent 2,337,437, issued December 21, 1943.

The main support member 7 of the luminaire illustrated in Figs. 1 to 4 is made up of a plurality of longitudinal sections rigidly joined to each other by interlocking joints 50 of the tongue and groove type separable by longitudinal displacement of the sections. The member 7 may be expanded laterally to accommodate more lamps by inserting additional trough shaped reflector sections 9 and 10 and a flat strip section between the bottom and top edges of the side sections having the reflecting surfaces 11 and 12. The inserted sections should, of course, have suitable interlocking tongue and groove surfaces for engaging those of the sections illustrated. The longitudinal sections of the support member may be extruded out of aluminum or other suitable metal. The surfaces 11 and 12 and the surface of the trough sections 9 and 10 facing the lamps are polished so as to have high reflectance for the light from the lamps.

When lateral expansion of the support member 7 is not considered necessary it may be made in one piece as shown in Figs. 5 and 6, in which the same numbers denote the same parts as in the embodiment of the Figs. 1 to 4. The other parts of the luminaire may be attached to the member 7 of Figs. 5 and 6 as described above in connection with Figs. 1 to 4. The member 7 shown in Fig. 5 may be extruded out of aluminum and that shown in Fig. 6 may be rolled in two sections 51 and 51' of sheet metal joined by a rolled over or welded seam.

The luminaire illustrated in Figs. 7 to 9 is similar to that shown in Figs. 1 to 4 except that the member providing the wiring channel and the reflecting surfaces is made up of three longitudinally extending hollow sections 52, 53 and 54 each providing a wiring channel. The side walls 55 of the sections are secured to each other by bolts 56 to form a long, wide, shallow main support member. As shown in Fig. 8, each of the sections has a flat top wall 57 and a bottom wall 58 shaped to form an elliptical reflector when the side walls 55 of the section are joined to those of other sections. One of the side walls of each of the sections 52, 53 and 54 has a longitudinally extending rounded tongue 60 protruding therefrom and the other of said walls has a longitudinally extending groove 61 therein to accommodate the tongue 60 of the section bolted thereto. The sections 52, 53 and 54 are thus rigidly fastened together by separable joints to make up

a rigid support for the lamps and the auxiliary equipment. The sections obviously need not be displaced longitudinally when joining them together or separating them.

In this embodiment the lamp holders 5 and 6 are supported by angle straps 64 and 65 held by bolts 66 to the top wall 57 of the outer sections 52 and 54 and the lamp ballast casing 31 is supported by the ballast cover 27 bolted to the top wall 57 of the center section 53. The bottom wall 58 of the center section 53 below the casing 31 has a removable portion 67 to give access to the lamp ballast. This portion 67 is supported at one end by a strap 68 resting on the adjacent parts of the wall 58 and at the other end by an extension similar to extension 40 of Fig. 4.

In addition to side shielding of the lamps, the luminaire shown in Figs. 7 to 9 also provides means for longitudinal shielding thereof. The said means comprises transverse louvers 70 fitting into transverse slots in the bottom surfaces 58 of sections 52, 53 and 54 and fastened to the longitudinal side shields 72. The louvers 70 and the shields 72 form a unit which is supported by hinges 73 engaging the straps 64 and 65 so that one end of the unit may be lowered out of the way when the lamps are to be replaced. Louvers 70 and shields 72 may be made of metal strips welded or soldered together. The strips may be opaque or have a multiplicity of small apertures therein so as to appear like translucent glass or plastic strips when illuminated by the lamps.

The luminaire of Figs. 7 to 9 may be laterally expanded by adding additional sections thereto similar to those shown.

What I claim as new and desire to secure by Letters Patent of the United States is:

1. An elongated shallow luminaire of the ceiling suspended type for tubular lamps comprising a main support in the form of an elongated flat hollow metal support member having a flat top wall, a bottom wall and side walls spaced apart to provide a wiring channel in the interior of said support member, the said bottom and side walls of said support member being light reflecting and shaped in the form of parallel juxtaposed longitudinally extending light concentrating troughs opening outwardly of said support member and having common longitudinal edges disposed in a plane parallel with said flat top wall, lamp holder supports secured to the top wall at the ends of said support member with portions thereof extending downwardly toward a common longitudinal edge of said troughs, a pair of lamp holders mounted on each of said support portions and extending through the sides of and terminating within the troughs having said common edge to engage the ends of and support tubular lamps within said troughs, electrical wires extending from said holders and along said wiring channel and means mounted at the ends of said support member for engaging suspending means for said luminaire.

2. A luminaire as claimed in claim 1 wherein the means for engaging the suspending means for the luminaire comprises an elongate lamp ballast cover attached to the top wall of said support member and extending from the end toward the center of said wall and wherein a lamp ballast is mounted under said cover and connected with the electrical wires in said channel.

3. A luminaire as claimed in claim 1 wherein the top wall of the metal member is cut out to provide openings adjacent its ends, wherein lamp ballast equipment is mounted in said openings.

and connected with the electrical wires in said channel and wherein the means for engaging the suspending means for the luminaire comprises lamp ballast covers over said openings and said equipment.

GEORGE R. BAUMGARTNER.
